ELECTROMAGNETIC MERCURY RELAY

John P. Keating, Elkhart, Ind., assignor to Durakool, Inc., Elkhart, Ind., a corporation of Indiana

Application April 6, 1946, Serial No. 660,031

10 Claims. (Cl. 200—112)

1

My present invention relates to an improvement in relays, and more particularly to mercury to mercury contact type of relays.

In the several embodiments of my invention herein disclosed I have shown and described mercury relays of the normally open type comprising a metal casing or shell which is adapted to serve as one electrode or terminal for the relay, and in which an electrode means is mounted in insulated relation and serving as a second electrode for the relay. The casing or shell provides for the support of a main body of mercury and a plunger means is contained within the casing or shell with the plunger means being adapted to be normally supported in floating relation in the main body of mercury. The plunger means is of a character to provide for the support of a second body of mercury in contacting engagement with the aforesaid electrode means and normally in insulated relation with respect to the main body of mercury in the casing or shell so that in the normal position of the plunger means the circuit through the relay is open. Upon energization of the coil of the relay the plunger means is attracted, and in its attracted position displaces the body of mercury in the shell or casing to effect contacting thereof with the second body of mercury of the plunger means to provide a mercury to mercury contact in effecting completing of a circuit between the casing or shell and the electrode means associated therewith. As will appear from the detailed description of the several embodiments of my invention I have provided several forms of plunger means for providing relays of the aforesaid normally open type and which plungers are of a character to provide a first relay of quick-make and quick-break type, a second relay of slow-make and slow-break type, and a third relay of quick-make and slow-break type. It will be understood that while my invention has particular utility for use in a relay of the metal casing or shell type, it will be understood that the casing or shell may be made of insulating material in which an electrode member is suitably mounted for contacting engagement with the main body of mercury in such a casing or shell, and which together with the aforesaid electrode means provides a pair of electrodes or terminals for the relays.

It is an object of my invention to provide a mercury to mercury contact type relay comprising a pair of electrode means arranged in insulated relation with respect to each other with one of the electrode means having contact with a main body of mercury supported in a casing for

2

the relay, and the other of the electrode means having contacting engagement with a second body of mercury supported in a displacer or plunger means normally disposed in floating relation in the main body of mercury, and which plunger means in its normal position insulates the main and second bodies of mercury from each other.

- 10 In a relay constructed, as last referred to, energization of the coil thereof will be effective to attract the displacer or plunger means drawing it downwardly into the main body of mercury in the casing or shell and which movement of the displacer or plunger means is effective to displace the main body of mercury into contacting engagement with the body of mercury supported by the plunger or displacer means. Preferably, the plunger means is constructed to provide for support of the second body of mercury in a manner to effect submerging of the same in the main body of mercury upon energization of the coil to assure that the mercury supporting means of the plunger is charged with mercury each time the coil is energized.
- 15 20 25 A further object of my invention is to provide a mercury to mercury contact relay as aforesaid having plunger means of a character to provide quick-make and quick-break of a circuit through the relay.
- 30 35 A further object of my invention is to provide a mercury to mercury contact relay having plunger means of a character to provide slow-make and slow-break of a circuit through the relay.
- 40 45 A still further object of my invention is to provide a mercury to mercury contact relay having plunger means of a character to provide quick-make and slow-break of a circuit through the relay.

A further object of my invention is to provide a plunger means as last aforesaid of a character to effect quick-make and quick-break of a circuit through the relay.

A further object is to provide a plunger means of the character noted to provide for slow-make and slow-break of a circuit through the relay.

A further object is to provide a plunger means of the character noted operable to effect quick-make and slow-break of a circuit through the relay.

The above and other objects and advantages of my invention will appear from the detailed description.

Now, in order to acquaint those skilled in the art with the manner of constructing and utilizing relays in accordance with my present invention, I shall describe in connection with the accompanying drawings certain preferred embodiments of my invention.

In the drawings:

Figure 1 is a detail vertical sectional view through one form of relay constructed in accordance with the principles of my present invention with the relay being shown in its normal open position;

Figure 2 is a view of a relay of Figure 1 showing it in its closed position;

Figure 3 is a detail vertical sectional view of another embodiment of my invention with the relay being shown in its open position;

Figure 4 is a view of the relay of Figure 3 but showing it in its closed position;

Figure 5 is a detail vertical sectional view of still another embodiment of a relay constructed in accordance with my invention with the relay being shown in its normally open position; and

Figure 6 is a view of the relay of Figure 5 showing it in its closed position.

Referring now to Figures 1 and 2, I have shown a relay 3 comprising a metal casing or shell 4 formed by a cylindrical tube of stainless steel or other suitable metal having a closed lower end wall 5. The casing 4 is commonly referred to in the art as an open envelope type of casing and in the several embodiments of my invention herein disclosed serves as one electrode or terminal for the relay. An electrode 6 serving as a second electrode or terminal for the relay extends inwardly of the open upper end of the casing 4 and is suitably mounted in insulated and preferably gas-tight relation thereto. The electrode 6 may be of any suitable form and, as shown, it is embedded in a glass bead 9 which in turn is carried in and fused to the inner surface of a metal sleeve 11. The electrode 6, the glass bead 9 and the sleeve 11 are first assembled into a unit before being mounted in the open end of the tube 4. The sleeve 11 at its lower end is provided with a radially outwardly extending flange 12, which flange is adapted to seat upon an annular steel washer or stop member 13, and which in turn seats upon an annular shoulder 14 preferably formed by the intersection of the enlarged counterbore at the open end of the casing with the smaller normal bore 15 of the tube. In assembling the relay, the steel washer 13, together with the unit formed by the electrode 6, the glass bead 9, and sleeve 11 are caused to occupy the position shown in Figure 1 after which an annular resilient gasket 16 of rubber or other suitable material is positioned over the sleeve 11 and seated upon the flange 12 thereof. The annular gasket 16 has an internal diameter equal to or slightly greater than the sleeve 11 for fitting over the latter. If desired an annular metal ring 17 may then be positioned on top of the resilient gasket 16. With the parts in the position described the open end of the casing 4 may be turned or spun inwardly to secure the annular ring 17 in the position shown. This turning in of the open end of the casing serves to

compress the annular gasket between the flange 12 of sleeve 11 and the annular member 17 to form a seal at the adjacent inner cylindrical surface of the casing. In the form of relay herein disclosed this seal is not depended upon to form a gas-tight seal, but rather serves principally to prevent mercury from escaping from internally of the casing. However, if desired the annular metal ring 17 may be dispensed with in which case the turned in end of the casing could be caused to engage the resilient gasket 16 to form both a gas-tight and liquid-tight seal. When the mounting means includes the annular member 17 a gas-tight seal may be formed between the turned in end of the tube, the metal ring 17, and the sleeve 11 by an annular ring of solder 18 which extends from the outer periphery of the casing or tube to the sleeve 11. As lead 19, as shown, is adapted to be secured to the switch casing by means of the ring of solder 18 to provide one lead for the switch. Also, a second lead 20, as shown, is secured as by soldering to the outer end of the electrode 6. The mounting of the electrode 6, as above described, of itself forms no part of my present invention and is more fully disclosed and claimed in the co-pending application of Herbert E. Bucklen III, Serial No. 647,867, filed February 15, 1946, now Patent No. 2,450,780, granted October 5, 1948, to which reference may be had. It will be understood that this is but one form of mounting means suitable for use in practicing my present invention and that this mounting means may vary widely in form. The electrode member 6, the glass bead 9 and the sleeve 11 are preferably made of materials having substantially matching thermal coefficients of expansion to prevent breaking away of these parts from each other due to heat generated in operation of the relay. Glasses and metals having such characteristics are now well known in the art with one such metal consisting of approximately 25% nickel, 17% cobalt, 0.3% manganese and the balance of iron. Likewise suitable borosilicate glasses, otherwise known as hard glasses, are suitable for use with the metal parts made of the aforesaid alloy.

The closed end 5 of casing 4, as is also known, is provided with a suitable tubulation 21 of known form and serves for evacuating the casing and filling the same with mercury. After the unit has been assembled, as described, it may be inserted in a cylindrical shell or enclosing housing 22 formed of any suitable insulating material. The open ends of the tube 22 are then filled with suitable plastic sealing composition 24 to seal the metal relay casing in the housing 22. It will be observed that the leads 19 and 20 are embedded in the plastic sealing composition adjacent the upper end of the relay and this sealing composition is preferably of a character providing a fluid-tight seal between the several elements assembled within the open end of the casing 4 and the enclosing housing 22. This arrangement of a metal casing in a housing of insulating material of itself forms no part of my present invention and is further described in detail in the above referred to application of Herbert E. Bucklen III.

The relay 3 further comprises an energizing coil 25 carried in a suitable supporting bracket 26 and surrounds the lower end of the tubular assembly comprising the metal casing 4 and enclosing insulating housing 22.

As previously related the casing 4 is preferably

of cylindrical shape and of suitable dimensions for receiving a substantially cylindrical plunger or displacer means 30. The displacer means 30 comprises a substantially cylindrical metal sleeve member 31 open at its upper and lower ends. A substantially cylindrical hollow sleeve member 32 made of suitable insulating material such as of ceramic composition commonly employed in mercury switch and relay construction, is contained within the cylindrical sleeve member 31. The lower open end of the sleeve member 31 is turned in as at 34 and which together with the inwardly turned in upper edge 35 of the sleeve member 31 into engagement with a conical shoulder 36 formed between the intersection of the reduced upper cylindrical end 37 of the member 32 with the main body portion thereof secures the metal sleeve member 31 and the insulating member 32 in assembled relation. As shown the member 32 is provided with a bore 38 extending inwardly from the upper end thereof with the closed end portion 39 thereof closing the lower end of the metal sleeve member 31. The plunger 30 constructed as described has normal floating relation in a main or first body of mercury 41 contained in the lower end portion of the casing 4 and a second body of mercury 42 is contained or supported in the bore 38 of the ceramic member 32 with the plunger means 30 in its normal floating position effecting engagement of the inner end portion of the electrode 6 with the body of mercury 42 contained within the bore 38 of the plunger means 30. It will be observed in the position of the plunger means 30 as shown in Figure 1 and with the coil means 25 de-energized that the relay is in normally open position.

Referring now to Figure 2 the plunger means 30 is shown in the position in which it is caused to be attracted upon energization of the coil 25 and in which position the plunger means 30 is caused to be submerged in the main body of mercury 41. The plunger means in this position displaces the latter body of mercury so that it is adapted to have contacting engagement with the body of mercury contained in bore 38 through the open top of the plunger means 30 completing a circuit between the electrode 6 and the casing 4 of the relay. Upon de-energization of the coil means 25 the plunger returns to its normal floating position of Figure 1, and the circuit is caused to be broken by separation of the first and second bodies of mercury from each other by the shearing action of the upper peripheral edge 44 of the ceramic cup-shaped member 32.

As shown the lower end of the ceramic insulating member 32 is preferably rounded so that when the plunger is in its attracted position as shown in Figure 2 the main body of mercury 41 will be disposed therebetween and the closed end 5 of the casing 4 so that upon de-energization of the coil means 25 the plunger will not tend to adhere or stick in its attracted position.

The outer cylindrical surface of metal sleeve 31 is of a diameter slightly less than the diameter of the internal cylindrical surface of the shell or casing 4 and the sleeve 31, as shown, carries on its outer cylindrical surface a plurality of ball elements 31' which have guiding engagement with the internal cylindrical surface of the shell or casing 4 in the vertical movement of plunger 30. The relative diameters of the sleeve 31 of the plunger and the internal cylindrical surface of the shell provide for preventing cocking or binding of the plunger in its movement in the shell. The incorporation of a guide means such as the ball elements 31' serves to provide for centering the

plunger and guiding it in its movement in the shell, and such ball elements are further described and claimed in the application of Herbert E. Bucklen III, and Glen L. Weimer, Serial No. 663,368, filed April 19, 1947, now abandoned. However, any other suitable known form of guide means may be used if desired. Also, it will be observed that the electrode is of a diameter relative to the diameter of bore 38 in ceramic insulator 32 so that in the transverse or lateral movement of the plunger in the shell the electrode 6 does not contact the surface defining the bore 38 so as to prevent any binding of the plunger on this score.

It will be observed that the relay shown in Figures 1 and 2 is of the mercury to mercury contact type having a normally open position and which provides upon the energization and de-energization of the coil means 25 quick-make and quick-break of a circuit through the relay 3.

Referring now to Figures 3 and 4 I have shown another relay 50 constructed in accordance with my invention in which the construction of the relay 50 is identical to the construction of the relay described in connection with Figures 1 and 2 except for the plunger means 51 thereof. The parts of the relay of Figures 3 and 4 bearing reference numerals 4 through 27 are identical with the parts of the relay of Figures 1 and 2 above described.

The plunger means 51 of the embodiment of my invention shown in Figures 3 and 4 comprises a substantially cylindrical metal sleeve 52 having a reduced upper cylindrical extension 53. A cup-shaped member 54 of insulating material likewise constructed of the known ceramic materials presently used in the construction of mercury switches and relays comprises an enlarged cylindrical end portion 55 disposed within the lower end of the cylindrical member 52 and adapted to be secured therein between an annular shoulder 56 formed adjacent the lower end of the cylindrical member 52 and the turned in outer edge 57 of the lower end of the latter. The member 54 is provided with an integral cylindrical extending portion 58 having a bore 59 extending inwardly from the upper end thereof with the cylindrical extension 58 being disposed within the cylindrical sleeve 52 and spaced therefrom to provide an annular recess 60 between the inner cylindrical surface of the member 52 and the cylindrical extension 58 of the insulating member 54. In this form of the invention the wall of the cylindrical portion 52 is provided with a metering port or orifice 62 opening into the lower end of the annular recess 60. The plunger means 51 of this form of my invention by virtue of the previously described construction thereof is adapted to have normal floating relation in the body of mercury 64 supported in the lower end of the casing 4, and the bore 59 is adapted to support a second body of mercury 65 in engagement with the inner adjacent end of the electrode 6 in the normal position of the relay. In

the normal position of the relay it will be observed that the second body of mercury 65 is out of contact with the first body of mercury 64 so that when the coil 25 is de-energized the relay is in open position. Referring now to Figure 4 I have shown the position the plunger means 51 occupies when the coil 25 of the relay is energized. Upon energization of the coil means 25 the plunger means 51 is immediately drawn to its attracted position to displace the body of mercury 64 in the casing 4. However the sleeve member 52 to-

gether with the reduced cylindrical extension 53 thereof is of sufficient length to prevent mercury from spilling over the open upper end thereof which necessitates the mercury passing through the metering orifice 62 gradually filling the annular recess 60 and thereafter coming into contacting engagement with the body of mercury contained within the bore 59 of the cylindrical portion 58 of the cup-shaped member 54. When this occurs a circuit is completed between the electrode 6 and the casing 4 of the relay. It will be understood that the one or more metering orifices 62 may be provided for effecting a time delay after energization of the coil 25 before the body of mercury in the lower end of the casing 4 is adapted to have contacting engagement with the body of mercury in the bore 59 of the cup-shaped member 54. Now when the coil 25 is de-energized the plunger means 50 will return to the position shown in Figure 3 of the drawing but the return of the plunger means to this position will not effect the immediate breaking of the circuit between the pair of bodies of mercury. The metering orifice 62 effects a time delay in the passage of mercury out of the annular recess 60 and which when the mercury drops below the upper open end of the cylindrical extension 58 of the member 54 effects opening of a circuit through the relay.

Also, preferably, the lower end of the member 54 is rounded as at 66 to prevent adhering of the plunger in its attracted position upon de-energization of the coil means 25 which feature has more specifically been referred to in connection with the embodiment of our invention described in connection with Figures 1 and 2.

The metal sleeve 52 of this embodiment of my invention also carries on its outer cylindrical surface a plurality of ball elements 52' with the electrode 6 and the bore 59 being of such diameters with respect to each other as described in connection with the electrode 6 and the bore 38 of the embodiment of my invention shown in Figures 1 and 2 so as to prevent any binding or cocking of the plunger in the relay shell or casing.

Referring now to Figures 5 and 6 I have shown still another form of relay constructed in accordance with my invention in which the relay shown in the latter figures is the same in all respects as the relays described in connection with Figures 1 to 4 except for the provision of a form of plunger means 70 adapted to effect a quick-make and slow-break of a circuit through the relay upon the energization and de-energization of the coil means 25 thereof. As before reference numerals 4 through 27 are identical to the parts previously described in connection with Figures 1 and 2 to which reference may be had.

The plunger means 70 of the relay of Figures 5 and 6 comprises a cylindrical metal sleeve 71 open at its upper end and having a cup-shaped member 72 of insulating material secured in the lower end thereof between a shoulder 73 formed adjacent the lower end of the sleeve 71 and the turned in edge 74 thereof to secure the member 72 in the position shown in the drawings in the sleeve 71. The member 72 secured in the position noted effects closing of the lower end of the metal sleeve 71 and it is rounded as at 75 for the purpose already noted.

The member 72 is provided with a cylindrical portion 76 extending co-axially of the metal sleeve sleeve member 71 and spaced therefrom to provide an annular recess 77 between the outer cylindrical surface of the cylindrical portion 76 75

and the inner cylindrical surface of the sleeve member 71. The cylindrical extension 76 is provided with a co-axially extending bore 78 which is adapted to receive and support a body of mercury 79. As before, the metal sleeve member 71 is provided with one or more metering ports 80 opening into the annular recess 77 adjacent the lower end thereof. The plunger means 70 with the coil 25 of the relay de-energized is adapted to be supported in floating relation in the main body of mercury 82 contained in the lower end portion of the relay casing 4.

In the position of the plunger means 70 as shown in Figure 5 the coil means is de-energized and it will be observed that the main body of mercury 82 in the relay casing 4 and the body of mercury 79 in the bore 78 of the cup-shaped member 72 are out of contact so that the circuit through the relay is open.

Referring now to Figure 6 the plunger means 70 is shown in the position it is caused to be assumed upon energization of the coil means 25, and it will be observed that the plunger 70 in its attracted position is effective to displace the main body of mercury 82 to be submerged therein whereupon the main body of mercury overflows the upper open end of the metal sleeve 71 to provide quick-make of a circuit between the electrode member 6 and the casing 4 of the relay. Now, upon de-energization of the coil means 25 it will be observed that the circuit between the electrode 6 and the casing 4 will not be opened or broken until the mercury in the annular recess 77 has metered through the metering orifice 80 in an amount to effect disengagement of the main body of mercury with the body of mercury in the bore 78 below the open edge of the cylindrical portion 76 so that a time delay is provided before opening of the circuit through the relay upon de-energization of the coil means 25. It is to be observed that the plunger means 70 of the embodiment of the invention of Figures 5 and 6 is substantially identical to the plunger means described in connection with the embodiment of my invention shown in Figures 3 and 4 except that the latter is provided with the reduced cylindrical extension 53 which is effective to prevent the spilling of mercury through the open upper end of the latter sleeve member upon energization of the coil means 25. However, by eliminating the cylindrical extension 53 and forming the main cylindrical body member 71 of the plunger means 70 of the proper length with respect to the amount of mercury disposed in the lower end of the casing 4 quick making of a circuit through the relay may be effected upon energization of the coil rather than the slow making of the circuit as in the relay of Figures 3 and 4.

As described in connection with the embodiments of my invention shown in Figures 1 through 4, the relay shown in Figures 5 and 6 has the plunger 70 thereof formed of a diameter slightly less than the internal diameter of the shell or casing 4 with the electrode 6 and the bore 78 being of appropriate diameters to prevent engagement of the electrode 6 with the surface defining the bore 78 in the limited lateral movement of the plunger in the shell or casing 4 as permitted by the differences in diameters between the external cylindrical surface of the plunger and the internal cylindrical surface of the casing or shell 4.

While I have shown and described mercury relays of the metal casing type it is believed that it will be obvious that mercury relays having a

casing or shell made of any suitable insulating material and having an electrode member extending thereto adapted to have continuous contacting engagement with the main body of mercury in the lower end of the casing may be substituted for the casing member 4 of the several relays above described. The operation of such relays would be the same as that of the relays described in that the plunger member would serve to establish a circuit between the electrodes when energized and to break the circuit when de-energized. In other words it will be clear that in lieu of the metal casing serving as an electrode a casing of insulating material provided with a suitable electrode having contacting engagement with a body of mercury in the casing could be utilised without departing from my present invention.

While I have shown what I consider to be the preferred embodiments of my invention it will be understood that various modifications and rearrangements may be made therein without departing from the spirit and scope of my invention.

I claim:

1. A mercury relay comprising a pair of electrode means insulated from each other with one of said electrode means having contacting engagement with a first body of mercury for said relay, plunger means open at the upper end thereof adapted to be normally supported in floating relation in said first body of mercury for supporting a second body of mercury in insulated relation with respect to said first body of mercury and in contacting engagement with the other of said electrode means, coil means adapted when energized to attract said plunger means to submerge the latter in said first body of mercury and thereby effect engagement thereof with said second body of mercury through the open upper end of said plunger means providing quick making of a circuit between said pair of electrode means, and said plunger means having metering means between said bodies of mercury through which mercury within said plunger means is returned to said first body of mercury for effecting a time delay in disengaging of said first body of mercury from said second body of mercury upon de-energization of said coil means and with said plunger means in its normal position.

2. A mercury relay comprising a pair of electrode means insulated from each other with one of said electrode means having contacting engagement with a first body of mercury for said relay, plunger means adapted to be normally supported in floating relation in said first body of mercury for supporting a second body of mercury in insulated relation with respect to said first body of mercury and in contacting engagement with the other of said electrode means, coil means adapted when energized to attract said plunger means to draw the latter into said first body of mercury and displace the same into contacting engagement with said second body of mercury to complete a circuit between said pair of electrode means, and said plunger means having metering means between said bodies of mercury for effecting a time delay in the contacting of said first body of mercury upon displacement of the same with said second body of mercury upon energization of said coil means and with said plunger means in its attracted position.

3. A mercury relay comprising a pair of electrode means insulated from each other with one of said electrode means having contacting engagement with a first body of mercury for said

relay, plunger means adapted to be normally supported in floating relation in said first body of mercury for supporting a second body of mercury in insulated relation with respect to said first body of mercury and in contacting engagement with the other of said electrode means, coil means adapted when energized to attract said plunger means to draw the latter into said first body of mercury and displace the same into contacting engagement with said second body of mercury to complete a circuit between said pair of electrode means, and said plunger means having metering means between said bodies of mercury for effecting a time delay in the contacting of said first body of mercury upon displacement of the same with said second body of mercury upon energization of said coil means and with said plunger means in its attracted position, and through which mercury within said plunger means is returned to said first body of mercury for effecting a time delay in disengaging of said first body of mercury from said second body of mercury upon de-energization of said coil means and with said plunger means in its normal position.

4. A mercury relay comprising a metal casing for supporting a first body of mercury therein and adapted to serve as one electrode for the relay, an electrode member mounted in insulated relation in said casing and serving as a second electrode for said relay, plunger means open at the upper end thereof disposed in said casing normally in floating relation in said first body of mercury comprising a metal sleeve member and a member of insulating material disposed internally of said sleeve member having a cup-shaped portion for supporting a second body of mercury in insulated relation with respect to said first body of mercury, and in contacting engagement with said second electrode said cup-shaped portion and said metal sleeve member forming a recess therebetween, coil means associated with said casing adapted when energized to attract said plunger means to submerge the latter in said first body of mercury and thereby effect engagement thereof with said second body of mercury through the open upper end of said plunger means providing quick making of a circuit between said electrodes, and said plunger means having metering means in communication with said recess through which mercury within said plunger is returned to the first body of mercury for effecting a time delay in disengaging of said first body of mercury from said second body of mercury upon de-energization of said coil means and with said plunger means in its normal position.

5. A mercury relay comprising a metal casing for supporting a first body of mercury therein and adapted to serve as one electrode for the relay, an electrode member mounted in insulated relation in said casing and serving as a second electrode for said relay, plunger means disposed in said casing normally in floating relation in said first body of mercury comprising a metal sleeve member and a member of insulating material disposed internally of said sleeve member having a cup-shaped portion for supporting a second body of mercury in insulated relation with respect to said first body of mercury and in contacting engagement with said second electrode, coil means associated with said casing adopted when energized to effect displacement of said first body of mercury into engagement with said second body of mercury to complete a circuit between said electrodes, and said plunger means having metering

means between said bodies of mercury for effecting a time delay in the contacting of said first body of mercury with said second body of mercury upon energization of said coil means and with said plunger in attracted position.

6. As an article of manufacture a plunger comprising a substantially cylindrical hollow metal sleeve, and a member of insulating material disposed within said metal sleeve and closing one end thereof, said last named member having a hollow cylindrical portion disposed co-axially of the axis of said metal sleeve with the outer cylindrical surface of said last named member being spaced from the inner cylindrical surface of said metal sleeve to define an annular recess open at its upper end therebetween, and metering orifice means for said plunger communicating with said annular recess.

7. As an article of manufacture a plunger comprising a substantially cylindrical hollow metal sleeve, and a member of insulating material disposed within said metal sleeve and closing one end thereof, said last named member having a hollow cylindrical portion disposed co-axially of the axis of said metal sleeve with the outer cylindrical surface of said last named member being spaced from the inner cylindrical surface of said metal sleeve to define an annular recess open at its upper end therebetween, and there being an opening in said metal sleeve member opening into said annular recess.

8. A mercury relay comprising a shell for supporting a main body of mercury, an electrode extending inwardly of the upper end of said shell, plunger means closed at the lower end thereof and adapted to be normally supported in floating relation in said main body of mercury comprising, an outer vertically extending metal sleeve member open at its upper end, and an inner insulator member having a vertically extending tubular extension open at its upper end and supporting a body of mercury in contact with said electrode member in the normal floating position of said plunger, said tubular extension and said metal sleeve forming a recess therebetween below the upper end of said tubular extension, metering orifice means in said metal sleeve opening into said recess, and coil means adapted when energized to draw said plunger means into said first body of mercury and displace the same so that the level thereof is disposed above the upper end of said tubular extension.

9. A mercury relay, comprising a shell for supporting a main body of mercury, an electrode extending inwardly of upper end of such shell, plunger means closed at the lower end thereof and adapted to be normally supported in floating relation in said main body of mercury comprising, an outer vertically extending metal sleeve member open at its upper end, and an inner insulator

member having a vertically extending tubular extension open at its upper end and supporting a body of mercury in contact with said electrode member in the normal floating position of said plunger, said tubular extension and said metal sleeve forming a recess therebetween below the upper end of said tubular extension, metering orifice means in said metal sleeve opening into said recess, and coil means adapted when energized to attract plunger means and submerge the same in said main body of mercury, said metal sleeve being of a length so that in the attracted position of said plunger means the upper end thereof is disposed below the level of the displaced mercury providing quick making of contact between said first and second bodies of mercury.

10. A mercury relay comprising a shell for supporting a main body of mercury, an electrode extending inwardly of the upper end of said shell, plunger means closed at the lower end thereof and adapted to be normally supported in floating relation in said main body of mercury comprising, an outer vertically extending metal sleeve member open at its upper end, and an insulator member having a vertically extending tubular extension open at its upper end and supporting a body of mercury in contact with said electrode member in the normal floating position of said plunger, said tubular extension and said metal sleeve forming a recess therebetween below the upper end of said tubular extension, metering orifice means in said metal sleeve opening into said recess, coil means adapted when energized to attract said plunger means and immerse the same in said first body of mercury, said metal sleeve in the attracted position of said plunger means being disposed above the level of the displaced mercury and with the upper end of said tubular extension being disposed below the level of the displaced mercury, whereby said metering means effects a time delay in the contacting of the displaced first body of mercury with said second body of mercury.

JOHN P. KEATING.
